JAMES CALDWELL STELFOX, OF WESTMINSTER, LONDON, ENGLAND, ASSIGNOR TO THE
U. G. I. CONTRACTING COMPANY, OF PHILADELPHIA, PENNSYLVANIA, A CORPOR-
ATION OF DELAWARE

PROCESS OF MANUFACTURING GAS

Application filed December 14, 1925, Serial No. 75,231, and in Great Britain December 14, 1924.

This invention has reference to the manufacture of gas by a known process in which coal or like material is carbonized in the upper part of a generator and passes as coke into the lower part thereof where it is alternately blasted with air to raise its temperature and with steam to produce water gas which is passed through the coal or like material above to carbonize or assist in carbonizing it. The object of the invention is to enable the process to be carried out efficiently as regards the transfer and utilization of heat for the production of water gas and the carbonization of the coal and to enable the mixed gas produced by completely gasifying the coal to be enriched when necessary without employing special or additional recuperators, carburetters or the like.

To this end, according to the present invention, the coke is blasted with air and the blast gases are led off from the coke without passing through the coal and are utilized to heat recuperative chambers and the coal is carbonized partly by the passage through it in a countercurrent direction with reference to the travel of the fuel through the carbonizing and gasifying chambers of the following; viz: hot water gas and excess steam produced by steaming the coke with steam superheated in the recuperative chambers, a portion of the produced coal gas and water gas mixed and superheated with the fresh gas making steam, and hot water gas produced by steaming the coke with "saturated" steam.

The lengths of the superheated and "saturated" steaming periods may be so adjusted as to provide the time for the requisite degree of carburetting in the recuperative chambers when not using these for the superheating of the steam. If desired, downrunning may be employed with "saturated" steam introduced at the junction of the coal and coke chambers and during this period carburetting also may be carried out or continued. The term "saturated" steam is intended to mean and include steam which has not been superheated in the recuperative chambers but it is immaterial whether such steam has been more or less superheated by

other means say for instance in a steam boiler superheater or the like.

As will be understood air blasting of the fuel may be effected between steaming with superheated steam and with "saturated" steam.

During the latter part of the air blow the blast gases may be passed through the coal, thereby helping to carbonize it, and these gases, which will be comparatively rich in carbon monoxide, and the gases evolved from the coal, may be led off preferably without passing through the recuperative chambers, and stored together with the water gas, if desired.

Under some conditions the utilization for carbonization of a portion of the coal gas and water gas mixed and superheated with the fresh gas-making steam may be suspended or dispensed with, the heat conditions in the generator being maintained, if necessary, by using a greater quantity of steam during the superheated steam run periods, or of air during the blasting periods, or of steam and of air during such periods.

Apparatus for carrying out the process may comprise as indicated in Fig. 1 of the accompanying diagrammatic drawings; generator *a* is formed with a gasifying portion generally below the connection *f* and a coal carbonizing portion above it and generally above the connection *f*, a recuperative chamber or chambers, that is to say a carburetter *b* and superheater *c* of suitable type, valved connecting passages *d*, *e* and *f* between a regenerative chamber, that is to say the carburetter, and the top, bottom and intermediate portions of the generator respectively and a valved connecting passage *g* between the top of the generator (by way of the passage *d*) and the outlet *h* from the recuperative chambers to storage after passing through wash box *x*; *d*, *e*, *f* and *g* indicate the valves in the connecting passages. Steam inlets *i*, *j* and *k* are provided respectively at the bottom of the generator, at the junction of the gasifying and carbonizing portions of same and in the outlet from the regenerative chambers to storage, a regulating valve *l* being interposed between the gas connection *g* with the

top of the generator and the steam inlet *k*, which is adapted to induce a backward flow through the regenerative chambers. This steam inlet may be located at some point 5 nearer the generator, if desired. *m* is the stack valve. *x* is the wash box having a gas outlet *y* therefrom. The usual connections are provided for the air blast to the fuel bed and for secondary combustion of blast products. *z* is an oil inlet, *w* is an air inlet to the carbureter and 22 is an air inlet to the superheater.

Some of the valves may be connected so as to be operated simultaneously or they may be 15 interlocked in any convenient way.

One valve interlocking and coupling arrangement suitable for apparatus as shown in Fig. 1 is diagrammatically illustrated by way of example in Fig. 2, which represents 20 in plan view the various pipes and valves in such a way that all can be seen easily, the full thick lines indicating couplings and the broken lines indicating interlocking means between valves. This arrangement will ensure 25 safety and convenience in working and provide for the automatic opening of the steam supply to the correct part of the apparatus when all the gas valves are set for a particular operation.

30 The valve *g*¹ is coupled with the valve *l* so that when *g*¹ is closed for an up-run or down-run with "saturated" steam the valve *l* is opened, and closed or partly closed as desired (according to the degree of gas circulation required) when the valve *g*¹ is opened for a 35 back-run. The valve *g*¹ is also coupled with the steam directing valve *q* to the back-run and down-run steam supplies so that when it is opened for a back-run, the steam is also 40 directed to the steam inlet *k* and, when the valve *g*¹ is shut, the steam is directed to the down-run steam inlet *j*, but is prevented from entering until the gas valve *e*¹ has been 45 opened for making a down-run, when the shut-off valve *p* to which the valve *e*¹ is coupled, is correspondingly opened. The gas valve *d*¹ is coupled with the steam valve *n* which directs the steam to the inlet *i* or to the back-run and down-run steam directing 50 valve *q* so that, when the valve *d*¹ is opened, the steam is directed to the inlet *i* and when it is shut it is directed to the directing valve *q* provided the shut-off valve *p* is opened by the gas valve *e*¹. The gas valve *e*¹ is mutually 55 interlocked with the generator air blast valve *r* so that the valve *e*¹ cannot be opened before the generator blast valve is shut and vice versa. The gas valve *e*¹ is also interlocked with the gas valve *d*¹ so that it cannot 60 be shut before *d*¹ is opened which will ensure an uprun being made with steam introduced at *i* to purge the generator bottom of water-gas before the same can be air blasted.

In addition the usual interlocking of the 65 stack valve *m* with the secondary air blast

valves of the regenerative chambers *b* and *c* may be employed, as also the usual interlocking of the carbureter oil supply with the generator air blast valve.

During the greater part of the air blow period, the valve *f*¹ will be open as will be the stack valve *m* and the valves *d*¹, *e*¹ and *g*¹ will be shut and the steam inlets *i*, *j* and *k* will be closed; during the latter part of the air blow period the valve *f*¹ and the stack valve may be shut and the valve *g*¹ opened, the blow-run gas passing from the top of the generator through the outlet *h* to storage. During a back-run the steam inlet *k* and the valves *e*¹ and *g*¹ will be open and the valves *d*¹ and *f*¹ closed. While the back-run is taking place the regulating valve *l* may be opened to a suitable extent and some of the mixed water-gas and coal-gas passing by way of the pipe *g* to the outlet pipe *h* may be re-circulated with and by means of the steam introduced at *k*. It will be understood of course that, if desired, re-circulation of the gas may be induced or carried out by other well known means. When making the uprun with steam not superheated in the recuperative chambers the steam inlet *i* will be open, the inlets *j* and *k* closed and the valve *d*¹ open and the valves *e*¹, *f*¹ and *g*¹ closed and during this period oil may be admitted to the regenerative chamber or carbureter *b* to enrich the gas. When making the down-run with steam not superheated in the regenerative chambers, the steam inlet *j* will be open and the steam inlets *i* and *k* closed, the valve *e*¹ will be open and the valves *d*¹, *f*¹ and *g*¹ closed. 100

I claim:

1. The process of manufacturing carburetted water gas which, when practiced in a single generator adapted to contain a descending column of fuel having coal at its upper end and coke at its lower end, a single carbureter and a single superheater, comprises a number of successive steps; the first step is air blasting the coke at the bottom of the column of fuel, leading off blast gases from a point beneath the coal in said column, and burning gases in the carbureter and in the superheater to store heat therein; the second step is in passing steam through the superheater and through the carbureter and through the entire fuel column in a direction opposite to the movement thereof forming water gas on the passage through the coke; the third step comprises recirculating a portion of the gas produced in the fuel column together with additional steam through the superheater and carbureter and through the entire fuel column in a direction opposite to the movement of the fuel column; the fourth step is passing saturated steam through the coke and through the coal in a direction opposite to the movement of the fuel column; the fifth step is introducing saturated steam to the fuel column at a point adjacent the 110

middle thereof and passing it through the coke in the direction of the movement of the fuel column thereby generating blue water gas, passing the water gas through the carburetter, carburetting the gas in the carburetter, then passing through the superheater, and storing the carburetted water gas.

- 5 2. In the manufacture of mixed water gas and coal gas when practiced in a single generator and a separate regenerative vessel; the improvement, which comprises maintaining a descending column of fuel in the generator, the column having a coal carbonizing zone at its upper portion and a coke zone at its lower portion, air blasting the coke in the lower fuel zone, leading off the air blast gases below the coal carbonizing zone and heating the regenerative vessel, passing saturated steam upwardly through the hot coke zone
- 10 20 and thereby generating water gas, passing the hot water gas through the coal to generate coal gas and assist the carbonization and simultaneously superheating a mixture of steam and recirculated water gas and coal gas
- 15 25 by passing the mixture through the heated regenerative vessel, admitting the superheated mixture of steam and gases to the hot coke zone simultaneously with the saturated steam, and passing the coke formed in the
- 30 coal carbonizing zone to the lower fuel zone.
